ABSTRACT OF THE DISCLOSURE

A dynamometer which has a housing provided with a fluid inlet and outlet and enclosing a set of interleaved stator and rotor disks. The disks are fabricated with work holes, the radius of a circle intersecting the centers of said holes gradually increasing from the disks on the inlet side of the housing to the disks on the outlet side to provide a cone shaped centrifugal flow of fluid through the dynamometer.

STATEMENT OF GOVERNMENT INTEREST

The invention described herein may be manufactured and used by or for the Government of the United States of America for governmental purposes without the payment of any royalties thereon or therefor.

BACKGROUND OF THE INVENTION

The invention relates to dynamometers and more specifically to a fluid dynamometer having a tapered disk configuration for distributing more evenly the power absorption throughout the stages of the dynamometer.

The uses of hydraulic dynamometers or water brakes for absorbing the power developed by the rotating shafts of prime movers are well known. For the most part, the prior art devices of this type utilized interleaved stators and rotors of identical construction. That is to say, that the diameter of a circle passing through the center of the work holes of each disk are the same for all the disks. With such a construction, under high speed operation encountered in the testing of turbine shaft engines used in the U.S. Navy, the first stage of the dynamometer being adjacent to the water inlet does most of the power absorption work, with progressively less work being accomplished by the remaining successive dynamometer stages, the last several stages doing practically no work. The theory of water dynamometer operation is based on the absorption of power by converting it to heat which is absorbed by the water. In the prior art designs, the first stage pushes the water to the outer limits of the housing. Although the flow holes are used to keep some of the water in the working holes area in the disks, the work absorption is ineffective, since forcing the water into a pattern at high speed operation tends to raise the water to steam temperature in the first few stages. Once the water converts to steam, the dynamometer loses complete load capability in those stages that are affected. This result occurs because the work holes are cylindrically disposed, and the water flowing in a centrifugal path by rotation of the rotor is forced to stop at each stator stage in order to pass through the work holes and so doing performs uncontrolled work.

SUMMARY OF THE INVENTION

This invention increases the efficiency and the life of the dynamometer by distributing the work, or power absorption, more evenly throughout all the dynamometer stages and in a controlled manner. This is accomplished over the prior art devices by reducing the power absorption capability in the first stage and forcing the remain-

2

ing stages of the dynamometer in succession to assume an equal share of the load capacity.

These beneficial results are achieved by gradually increasing the bolt circle, that is, the diameter of a circle intersecting the centers of the work apertures in successive disks commencing from the disk on the inlet side to the disk on the outlet side of the dynamometer housing. In addition to providing a conical configuration to the corresponding work holes on successive disks, a spiral configuration is achieved by radially indexing the work holes in successive disks a given angular displacement. This conical-spiral arrangement of the work holes thus conform generally to the flow of the working fluid, usually water, to which is imparted by the rotors a conical-spiral flow by centrifugal force. Thus the fluid is able to flow from one dynamometer stage to an adjacent stage without the necessity of a complete stop in its rotary motion, as was the case in the prior art dynamometers.

STATEMENT OF OBJECTS OF INVENTION

A principal object of this invention is to increase the life of a fluid dynamometer by distributing its power absorption throughout the various stages of the dynamometer, and a corollary object is to eliminate instability in operation of the dynamometer and erosion caused by the water flushing to steam in an overloaded stage.

Another important object is to enable a given size dynamometer to increase the load capacity and thereby enable the testing of larger horsepower engines.

Other objects and many of the attendant advantages of this invention will be readily appreciated as the same becomes better understood by reference to the following detailed description when considered in connection with the accompanying drawings wherein:

FIG. 1 is a vertical cross-section of a six-stage dynamometer showing the novel tapered configuration of the stators and rotor disks;

FIGS. 2 and 3 are side elevation views of No. 1 rotor disk and No. 6 rotor disk, respectively, from the set of six rotor disks;

FIG. 4 is a table tabulating pertinent dimensions of all the rotor disks in the entire set;

FIGS. 5 and 6 are enlarged side elevation views of No. 1 stator disk and No. 6 stator disk, respectively, of the set of six stators;

FIG. 7 is a table tabulating the pertinent dimensions of all the stator disks in the entire set; and

FIG. 8 is a side elevation view of a set of stator disks, partially in section, showing the conical-spiral disposition of the work holes, and for clarity illustrating only one corresponding work hole in each of the successive disks in the set.

DESCRIPTION OF THE PREFERRED EMBODIMENT

Referring to the drawing where like numerals refers to a corresponding part throughout the various figures there is shown in FIG. 1 a basic Navy-designed six stage dynamometer or water brake 10.

All existing components of the illustrated dynamometer are of conventional design except for the unique construction of rotor disks 12 and stator disks 14, the details later to be described, which form the essence of this invention. In the illustrated embodiment are shown a set of six rotor disks, forming a six stage device. The dimensions of the rotor and stator disks hereinafter described are taken from a model actually tested with a U.S. Navy designated T64 Turbo Shaft engine developing approximately 3,750 H.P. It is apparent that the number, dimensions and configuration of the rotor and stator disks can be varied to

accommodate specified requirements for the dynamometer.

Dynamometer 10 comprises a housing 16 formed of a cylindrical casing 18 being closed at the ends by an inlet bell end 20 and an outlet bell end 22. Inlet bell 20 is provided with inlets 24 for the admission of the brake fluid, usually water, to housing 16, and bell end 22 is provided with outlets 26 for the discharge of the water. A shaft 28 is rotatably mounted in the housing on a pair of ball bearings 30 set in the bell ends, the shaft being provided with a splined connection 32 for coupling to the prime mover, not shown.

The set of six rotor disks 12 are suitably keyed at 34 to shaft 28 for rotation therewith. The rotor disks are spaced apart from each other by any suitable means, such as an integral flanged hub portion 36, to accommodate the stator disks 14 which are interleaved therewith.

The details of the set of rotor disks are illustrated in FIGS. 2 and 3; FIG. 2 illustrating No. 1 rotor disk and FIG. 3 illustrating No. 6 rotor disk, the numbering system starting from inlet 24 and ending at outlet 26 in the housing. FIG. 4 is a table specifying the dimensions and configuration of all six rotor disks in the set. The construction details of the rotor and stator disks are generally similar, and the detailed description of the rotor disks will apply to the stator disks with exceptions noted, such as dimensions. As is seen from FIGS. 2-4, each rotor disk 12 may be provided with an annular group of work holes 38 and an annular group of flow holes 40, each group concentrically arranged, with the set of work holes being outermost. As is well known in the art, the operation theory of this type of dynamometer is the absorption of power of converting the energy to B.t.u.'s (raising the temperature of the water flowing through the brake). This is accomplished by the shearing of the water through the work holes. The flow holes are used to pass the excess water from one stage to another to provide fluid for the succeeding stages. The diameters of all the work holes in each group on a given disk are identical, as are the diameters of all flow holes in each group on the same disk, although in most instances the diameters between the holes in two groups on the same disk will be different. In addition, the diameter of work holes and flow holes between the various disks will vary as can be seen from the chart in FIG. 4 where it will be noted that the diameters of both the work holes 38 and the flow holes 40 gradually increase in size on the disks from No. 1 through to No. 6.

In the illustrated embodiment, each rotor disk, as well as each stator disk as will be hereinafter noted, have 18 work holes and 18 flow holes, however, these numbers may be varied to tailor the dynamometer to specific work requirements. The experimental results of one test in providing different numbers of work holes and flow holes in successive disks of the sets will be described under the heading "operation."

An important feature of the novel disk design is the geometric pattern of work holes 38 and flow holes 40 in the disks of the set. It has been found in practice that to achieve the objects of the invention, the bolt circles of both the work holes and the flow holes, i.e., the circles intersecting the centers of the respective sets of holes, should gradually increase successively in all the rotor disks in the set commencing from the No. 1 disk adjacent the inlet 26 through to the No. 6 disk adjacent outlet 26, as can be observed from the table in FIG. 4. Likewise the diameters of each of the work holes 38 and the flow holes 40 increase in diameter, as is also seen on the table, so that the work absorption of the brake will be equalized throughout the six brake stages.

In addition, it is believed that by increasing the outer diameter of the rotors from No. 1 to No. 6, giving the set a tapered configuration, assists in the equalizing of the work absorption of the brake stages. The successively increasing diameter of the bolt circles enable the later stages of the brake to absorb more work than is possible

under prior art configurations where all the respective bolt circles are of the same diameter. Thus, it is apparent that the holes in the six rotor disks will assume a conical or tapered configuration from the inlet to the outside sides of the housing that generally conforms to the cone of water caused by the centrifugal force created by the rotors. By such a design, coupled with the spiral pattern described in the following description the water is able to move and advance from one stage to the next without the necessity of a complete stop in its rotary motion at each dynamometer stage. This provides better control of the load capability of each stage.

In addition to the above described tapered design, it was found desirable to provide the holes of the rotors and stators with a spiral configuration with reference to the direction of rotor rotation. In the case of rotors, the spiral arrangement increases water flow through the brake if it is counterclockwise to the direction of rotor rotation, which as will be later observed is opposite to the spiral provided on the stators. It is reasoned that after the water passes through the work holes in the stator the water lags because it is not moving as fast as the next rotor and thus it passes through an after hole in the stator.

It has been found desirable on the model tested of the preferred embodiment that there be a 5° lag counterclockwise in each successive rotor of the set. This counterclockwise spiral construction configuration is accomplished in the rotors of FIGS. 2 and 3 by successively staggering each keyway 34 in the rotor disk 5° with reference to a given work hole 38. In FIG. 2, which illustrates rotor #1, keyway 34 is on a centerline 2 passing through the center of work hole 38a. In FIG. 3 which illustrates rotor #6 in the set, centerline 42 passing through corresponding work hole 38f is displaced 25° counterclockwise with reference to keyway 34, the intervening rotor disks, not illustrated, each lag 5° with respect to the disk immediately forward. It will be noticed in FIGS. 2 and 3 that the centers of work holes 38 and flow holes 40 maintain a uniform staggered relationship on each disk.

As previously noted, the configurations of stator disks 14 are similar in many respects to the configurations of rotor disks 12, and the differences will be described. Stator disks 14 may be fabricated in halves, as shown in FIGS. 5 and 6, to accommodate a split housing and are provided with oppositely disposed peripheral keyways 44 partially in each half for assembly to a pair of corresponding keys 46 on the inner bore of split cylinder 18 (FIG. 1). A series of annular spacers 48 are provided between the stator disks to perform two functions. First, spacers 48 lock the stators in spaced relationship with the rotor disks, and secondly, by decreasing the inner diameter of spacers 48 in direct relationship with the decreasing outer diameter of the rotor disks a substantial uniform water volume as achieved in the various stages of the dynamometer. As is obvious from FIG. 1, the outer diameter of the stator disks must be of the same diameter to fit within casing 18, however, it is preferable that the inner diameters at 50 be increased on a corresponding tapered configuration from #1 to #6 stator in the set so as to allow a progressively larger passageway for a supply of water flow to move toward the rear of the brake without performing work, in a similar manner as is performed by the flow holes in the stator disks. This is to provide a supply of water for the rear stages.

Referring to FIGS. 5-7 inclusive, there is shown in FIG. 5 a front elevation view of stator #1 having an outer group of eighteen flow holes 52 and an inner group of eighteen work holes 54. Although the stator and rotor disks have the same number of holes in each set, the dimensions of the holes between the different disks of the set differ are shown in the table of FIG. 7. Whereas the diameters of the flow holes and work holes on the rotor disks gradually increase from #1 to #6 rotors as was seen in the table of FIG. 4, on the stator disks in FIG. 7 the diameter of the flow holes decrease as the diameter of the work holes

increase in dimensions, in order to provide a controlled amount of temperature rise in each stage to equalize the work performed therein.

Whereas the work holes and the flow holes in the rotors have a counterclockwise spiral, i.e., away from the direction of rotor rotation, in the stator disks the spiral of the work holes and flow holes are in an opposite direction, namely, in a clockwise rotation. The clockwise spiral configuration on the stator disks is illustrated in FIG. 8 which discloses only one given work hole in each of the six stator disks, the flow holes not shown for simplicity in illustration.

To provide the clockwise spiral configuration to the holes in the stator disks in FIGS. 5 and 6, the holes in each stator disk are advanced 5° ahead in each succeeding stator disks, so that the holes in stator disk #6 will be 25° advanced with regard to the holes in stator #1 (just opposite to the lagging effect in the rotor disks described in FIGS. 2 and 3).

In summary, as the spiral of the holes in the rotor disks are counterclockwise and the spiral of the holes in the stator disks are clockwise, the combined spiral configuration of both disks is in effect a zig-zag pattern extending through the brake with the path being generally in the direction of rotation of the rotor.

Operation

The operation of the invention brake is quite similar to the operation of a conventional brake in that the shearing action on the water by the work holes in both disks raises the temperature of the water and thus absorbs power by converting the energy into heat. It is important that there be a minimum pressure arise in the water as it progresses through the brake—just the opposite to the requirements of a pump. It was found that the prior art problems of uneven distribution of power absorption and of erosion of the parts could be avoided by providing a conical spiral path for the water as it flows through the brake, and by controlling the distribution of water passing through the work holes by varying the size of the holes and the passageways through the cores of the stators.

A series of actual tests conducted on variations of the novel brake design with a T64 turbo shaft engine revealed some interesting results.

One attempt to create a spiral flow through the brake consisted of increasing the number of work holes and flow holes by one in each succeeding stage, i.e., from 13 in stator #1 to 18 holes in stator #6, and at the same time successively increasing the bolt circles of the group of holes. This necessitated that one hole one each stage be the starting point therefore without spiral. After three hours of operation, upon disassembly a serious wear-pattern was found in that an erosion caused by cavitation occurred at the spiral starting holes in the disks at the inlet stages. Although the total load capacity appeared to be satisfactory, the distribution among the stages was poor with the stages near the inlet taking most of the load. It was believed that the unequal number of holes in the disks actually upset the spiral condition of the water since the erosion occurred on only one side of the disks.

Another test involved a brake design in which 18 holes used uniformly for all work holes and flow holes and on all stator and rotor disks. The inner core diameter of all stator disks was the same. The following results

Setting	H.P.	Pressure		Temperature		Flow, g.p.m.
		In	Out	In	Out	
Max. R.....	2,980	96	110	80	185	134
Mil.....	2,830	93	102	80	185	125
Norm. R.....	2,490	95	87	80	185	112
75%.....	1,960	70	60	80	175	88

Upon disassembly it was noticed that a similar erosion occurred around the holes as the previous run test because the rotors were inadvertently assembled backwards, providing an uneven flow through the brake in a similar man-

ner as the previous example discussed. Thus, by two different means, a disturbance of the natural water flow through the brake caused serious erosion and provided additional emphasis on later results.

- 5 The next test conducted corrected the improper orientation of the rotor disks, and also gradually increased the inner core diameter of successive stators, as it was felt that the flow holes did not pass a sufficient amount of water in effect starving the rear stages of the brake. The results of 10 this test are illustrated below in test #6.

Setting	H.P.	Pressure		Temperature		Flow, g.p.m.
		In	Out	In	Out	
Max. R.....	3,170	98	98	70	165	161
Mil.....	3,000	92	95	70	160	156
Norm. R.....	2,600	76	98	70	155	148
75%.....	2,050	55	67	75	155	117

Comparing the results in test #4 with test #6 it can be seen that increasing the inner core diameter of the stators allowed more water flow and a greater workload capability. With the increase in water flow there was a substantial drop in the water discharge temperature which is most desirable.

- 20 Another test was conducted as test #6 to determine the effect of increasing the diameter of work and flow holes by $\frac{1}{16}$ ". The results are indicated below as test #8.

Setting	H.P.	Pressure		Temperature		Flow, g.p.m.
		In	Out	In	Out	
Max. R.....	3,110	67	62	70	150	180
Mil.....	2,970	70	55	70	145	173
Norm. R.....	2,350	58	50	70	145	146
75%.....	1,773	12	38	70	145	111

35 Comparing the results of test #8 with test #6, increasing the diameter of both the work and flow holes had the desired effect of increasing the water flow while decreasing both the discharge temperature and pressure. The low discharge temperature had the effect of causing a slight instability in the engine but raising the water temperature by slightly closing the discharge valve eliminated the instability.

- 40 If it is desired to increase the water flow, the diameter of the stator flow hole could be increased slightly to achieve this results.
- 45 From the above description, it has been shown how the efficiency of the water brake can be increased which materially lengthens the operating life. In addition by more uniformly distributing the workload capability over all the stages of the brake, a larger rated prime mover can be accommodated. As previously noted the number of work and flow holes, dimensions, number of stages may vary with each specific requirement.

55 In summary, the objects of the invention have been achieved by using a tapered configuration in several aspects of the dynamometer. Firstly, the holes in the stator and rotor disks were designed along a taper i.e. conical-spiral to conform to the natural flow of water through the brake. Secondly, the outer diameter of the rotor disks are tapered, thirdly, the inner core diameter of the stators are designed on a taper to provide an increased passageway for the non-working flow of water, and lastly, the spacers between the stator disks are tapered to maintain a uniform water volume in the various dynamometer stages.

60 Obviously many modifications and variations of the present invention are possible in the light of the above teachings. It is therefore to be understood that within the scope of the appended claims the invention may be practiced otherwise than as specifically described.

65 What is claimed is:

- 70 1. A hydraulic dynamometer comprising:
a housing defining a generally cylindrical space having an inlet and an outlet for the passage of a fluid;
a shaft journaled in said housing;
a set of rotor disks mounted on said shaft for rotation therewith;

a set of companion stator disks fixedly mounted interiorly on said housing; the stator disks interleaved in spaced relation with the rotor disks forming a plurality of braking stages; said rotor disks and said stator disks each having a plurality of work apertures extending therethrough, the diameter of a circle intersecting the centers of said apertures gradually increasing on successive disks commencing from the disks on the inlet side to the disks on the outlet side of said housing; whereby fluid passing through the housing from the inlet to the outlet let will move through the stages in a generally conical flow following the centrifugal force imparted to the fluid so that the power absorption of the dynamometer will be distributed among all the several stages.

2. The dynamometer of claim 1 wherein each stator disk is provided with an inside diameter which increases in each successive disk from the inlet to the outlet side of the housng.

3. The dynamometer of claim 1 wherein the outer diameter of each rotor disks increase in each successive disk commencing from the inlet to the outlet side of the housing.

4. The dynamometer of claim 3 wherein the stator disks are spaced apart by spacers, the inner diameters of the spacers vary directly with the outer diameter of the corresponding rotors to provide a conical passageway for the water through the housing.

5. The dynamometer of claim 1 wherein said disks have inner and outer sets of concentric apertures extending therethrough, one set of concentric apertures comprising said work apertures and the other set of concentric apertures defining flow apertures.

6. The dynamometer of claim 5 wherein the outer set of concentric apertures on the rotor disks and the inner set of concentric apertures on the stator disks are work apertures.

7. The dynamometer of claim 6 wherein the corresponding apertures of successive disks are arranged to provide a spiral configuration.

8. The dynamometer of claim 7 wherein each disk has the same number of apertures.

9. The dynamometer of claim 8 wherein the spiral configuration of the corresponding apertures on successive disks is provided by angularly displacing each successive disk a given angular displacement.

10. The dynamometer of claim 9 wherein the spiral configuration of the corresponding apertures in the stator disks extends in the direction of rotation of the shaft, and the spiral configuration of the corresponding apertures in the rotor disks extends in a direction opposite to shaft rotation.

11. A hydraulic dynamometer comprising: a housing defining a generally cylindrical space having an inlet and an outlet for the passage of a fluid; a shaft journaled in said housing; a set of rotor disks mounted on said shaft for rotation therewith; the outer diameter of such disks gradually increasing in successive disks commencing from the disk at the inlet to the disk at the outlet; a set of companion stator disks fixedly mounted interiorly on said housing each having an inner diameter which gradually increases in successive disks commencing from the disk at the inlet to the disk at the outlet, the stator disks spaced apart by a plurality of spacers forming with the interleaved rotors a plurality of braking stages, said spacers having an inner diameter that increases gradually in direct relation to the outer diameters of the rotor disks forming a conical water passageway therewith; selected rotor disks and said stator disks having a set of outer and inner circumferentially disposed work apertures respectively and a set of inner and outer flow apertures respectively extending therethrough, the diameter of a circle intersecting the centers of said apertures gradually increasing on successive disks in each set from the disks on inlet side and extending to the disks on the outlet side of said housing; the apertures on successive disks being staggered to provide a spiral configuration to the corresponding apertures in the disks of the set; whereby fluid passing through the housing in the conical passageway from the inlet to the outlet will move through the stages in a generally conical spiral flow following the centrifugal force imparted to the fluid so that the power absorption of the dynamometer will be distributed among the several stages.
